UNITED STATES PATENT OFFICE.

CLIFFORD H. MILES, OF WATERBURY, CONNECTICUT.

TACK AND STAPLE PULLER.

No. 894,969.

Specification of Letters Patent.

Patented Aug. 4, 1908.

Application filed July 16, 1907. Serial No. 384,008.

To all whom it may concern:

Be it known that I, CLIFFORD H. MILES, a citizen of the United States, residing at Waterbury, in the county of New Haven and State of Connecticut, have invented a new and useful Improvement in Tack and Staple Pullers, of which the following is a specification.

This invention relates to tack and staple pullers, the object being to provide a tool which is very cheap and simple in construction, and one which will draw a tack or staple without any danger of cutting the head off the same.

Another object of my invention is to provide a tool which is so constructed that when the jaws are closed on the tack and pressure applied to the handle, the tack will be drawn upwardly without any danger of breaking the head off, as is the case with devices of this character now in use.

With these and other objects in view, the invention consists in the novel features of construction, combination and arrangement of parts, hereinafter fully described and pointed out in the claims.

In the drawings forming a part of this specification:—Figure 1 is a side view of my improved tool, showing it in position to draw a tack. Fig. 2 is a side view of the tool showing it in the act of drawing a tack. Fig. 3 is an end view of the tool, a portion of the handle and shank being shown in section. Fig. 4 is a perspective view of the shanks carrying the gripping jaws. Fig. 5 is a side view of the tool in position to draw a staple. Fig. 6 is a side view of the tool in the act of drawing the staple.

In the drawing A indicates a pair of flat shanks provided with lugs A' and having curved offset pointed gripping jaws A² at their lower ends. The upper end of one shank is bifurcated and the end of the other shank is provided with a tongue which is adapted to fit in the bifurcation, and be bent down over the side of the shank, so as to securely lock the shanks together, so that they can be readily secured in an ordinary handle B.

The gripping jaws are provided with apertures in alinement with each other, in which

is secured a rivet C on which is mounted, between the jaws a rocker member D which is provided with an intervening cut out portion forming a jaw D' which is adapted to co-act 55 with the jaws A², when placed over a tack. One end of the member D being provided with an enlargement D² which is engaged by the lugs A', so as to prevent the jaws from cutting off the head of the tack, when the lever is pressed downward. A lug D³ is formed on the member D, to the other side of the pivoted point which is adapted to engage the shank when the tool is used for drawing a staple. The member D being provided with a cam surface D⁴ adapted to engage the floor or wood in which the tack is driven, and with a curved bearing surface D⁵ for engaging the floor or wood into which the staple is driven when used for drawing a staple. 70

The operation of the tool for drawing a tack is as follows:—The tool is placed over a tack as shown in Fig. 1, and by pressing handle rearwardly and downwardly, the point of the jaw A² will be forced under the head of the tack, and at the same time the jaw D' of the member D will be forced under the other side of the head, and as further pressure is applied to the handle, it will ride on the cam surface of the member, the lug A' being 75 brought into engagement with the enlargement D², which forms a stop which prevents the jaws from cutting the head off the tack, as it is pulled out.

The operation for drawing a staple is as 85 follows:—The jaw D' is forced under the cross bar of the staple, and as pressure is applied to the handle, the shanks are brought into engagement with the lug D³ which prevents it from moving any further, and as further pressure is applied, the jaw D' will be forced further under the staple and drawn upwardly as the curved bearing surface rides over the floor which will lift the staple out without any danger of breaking the same. 95

Having thus fully described my invention, what I claim as new and desire to secure by Letters Patent is:—

In a tack and staple puller, the combination with a pair of shanks provided with lugs 100 adapted to be secured together having offset curved pointed jaws at their lower ends, of a

handle secured over said shank, a rocker member pivotally mounted between said jaws, having a curved bearing surface at one end and a curved cam at the other end, said

brought into engagement with each other, for holding said jaws apart.

5 cam surface being provided with an enlargement, a co-acting jaw formed on said member, said lug and enlargement adapted to be

AFFORD H. MILES.
